CORSAGE HOLDER

Albert J. Pujol, Astoria, Long Island, N. Y., assignor to Cartier, Inc., New York, N. Y., a corporation of New York

Application August 16, 1940, Serial No. 352,847

5 Claims. (Cl. 24—6)

This invention is an article of jewelry adapted to be worn by ladies to hold a corsage securely in place, without damage to the stems of the flower or flowers and in such manner as to give to the assembly a neat and finished appearance. The article is so constituted that it may be associated with the stems of a corsage and then mounted upon the person by attaching it to a garment by means of a pin, forming a part of the article.

Speaking generally, the article, in its preferred form, comprises an appropriate foundation, to the back of which is secured a pin for mounting the same upon a garment and on this foundation is supported a clamping device adapted to be manually opened to permit the stems of flowers to be placed therein and, when released, adapted to be spring pressed into a clamping position to firmly secure the flowers to the foundation.

The clamping device comprises, in its preferred form, six links pivoted to one another and collectively forming a substantially hexagonal frame. One of the side members of this frame is provided with projecting lugs, while the two adjacent sides are formed with spring tongues bearing against said lugs in such manner as to normally cause the frame to collapse for the purpose of clamping the stems of flowers within its confines. Diagonal pressure may, however, be applied to the frame to cause said frame to be distended or opened for the purpose of permitting the introduction of the stems or to permit of their release, as the case may be. All parts of the article may be ornamented in any appropriate way and may be studded with gems or artificial stones.

Features of the invention other than those adverted to, will be apparent from the hereinafter detailed description and claims, when read in conjunction with the accompanying drawing.

The accompanying drawing illustrates one practical embodiment of the invention, but the construction therein shown is to be understood as illustrative, only, and not as defining the limits of the invention.

Figure 1 is a front elevation of an article embodying the present invention, showing a corsage held in place therein.

Figure 2 is a transverse section taken on the line 2—2 of Figure 1.

Figure 3 is a plan view of the device showing the three upper links removed so that the three lower links and the foundation may be clearly seen.

Figure 4 is an underneath perspective of one of the upper links.

Referring to the drawing, 1 is a foundation which may be of any suitable shape, but may be conveniently made in the form of an annulus. It is generally made from metal. At two diametrically opposite points in its inner periphery there is pivoted to the foundation 1 a pair of links 2, by means of pivot pins 3, and the opposite ends 10 of these links 2 carry pivot pins 4 which are connected to brackets 5 formed rigidly with and on the under sides of links 6. By this connection, the links 6 are pivotally supported through the links 2 upon a foundation 1.

15 The inner ends of the links 6 are hinged, by means of pivot pins 7, to the opposite ends of a lower center link 8. This lower center link has lugs 9 which project outwardly beyond the pivots 7 and bear against the upper sides of spring 20 tongues 10 formed by slitting the links 6 longitudinally at 11, as shown best in Fig. 3. The tongues 10 are so tensioned that, as they bear against the under sides of the lugs 9, they tend to force the links 6 and 8 into alinement and 25 in so doing normally hold the links 6 in slightly depressed seats 12 formed to receive them in the foundation.

The outer ends of the links 6 are secured, by 30 pivots 13, to the two lateral upper links 14, while the inner ends of the links 14 are connected to the outer ends of the center upper link 15 by pivots 16. When the spring tongues 10 act upon the lower links 6 as stated, so that they tend to force them into alinement, this action draws 35 the upper links downwardly and into positions wherein the pivots 13 and 16 occupy substantially the same plane.

It will be noted, however, that the upper lateral links 14 project outwardly beyond the pivots 13 and form finger pieces 17. When pressure is applied to these finger pieces in the direction of the arrows 18, as indicated in Figure 2, the tension of the spring tongues 10 will be overcome and the links 6, 14 and 15 may be extended into 45 the dotted line position in Figure 2, so that the hexagonal frame, formed by these center links and the link 8, is opened up to permit the passage of the stem or stems of flowers therethrough. When pressure on the finger pieces 17 is released, the spring tongues 10 will again collapse the hexagonal frame into the full line position of Figure 2 to grip and hold the flower stems. Thus the frame, which constitutes the gripping device hereinbefore mentioned, may be 50 distended or collapsed at the will of the user.

To facilitate the gripping and holding of the flower stems, the inner sides of one or more of the links may be provided with serrated ribs 17, as shown best in Figure 4, although these may be omitted if desired as they are not absolutely necessary.

Any appropriate means may be provided for attaching the foundation to the clothing of the wearer. For the purpose of illustration, I have shown a bracket 19 secured to the back of the foundation and carrying a pair of pins 20 adapted to be passed through the garment.

It will of course be understood that all exposed parts of the device which are visible when worn may be enameled or otherwise ornamented or may be studded with stones or precious gems.

The device of this invention may be made in various sizes, but, in practice, it is found that when made relatively small, it will hold corsages of widely varying sizes with thorough satisfaction and will not appear unduly prominent.

In the form of the invention which I have shown in the drawings, the links 6 are pivoted to the foundation through interposed links 2. It is possible, however, to pivot the links 6 directly to the foundation if the pivots pass through slots, so as to permit of sufficient loss motion to compensate for the opening and closing movements of the clamping device. The interposed links 2, however, are preferred where cost of manufacture is not important, for they eliminate loss motion and result in a construction which operates more smoothly.

The foregoing detailed description sets forth the invention in its preferred practical form, but the invention is to be understood as commensurate with the appended claims.

Having thus fully described the invention, what I claim as new and desire to secure by Letters Patent is:

1. A corsage holder comprising a clamping frame formed from a plurality of links pivoted to one another, one of said links having lugs projecting beyond the pivotal connection with adjacent links and said adjacent links having spring tongues bearing against said lugs to nor-

mally collapse said clamping frame to grip flower stems passing therethrough, and means for attaching the clamping frame to a garment.

- 5 2. A corsage holder comprising a clamping frame formed from a plurality of links pivoted to one another with one of the links having lugs projecting beyond the pivots thereof and with spring tongues on adjacent links bearing against said lugs in a direction to normally collapse said 10 clamping frame upon the stems of flowers passing therethrough, a foundation, means for supporting said clamping frame on the foundation, and means for securing the foundation to a garment.
- 15 3. A corsage holder comprising a foundation, links pivoted to the foundation, a clamping frame pivoted to said links and comprising additional links pivoted to one another, certain of the links of the clamping frame having formed thereon 20 resilient tongues bearing against another link of said clamping frame to normally collapse the clamping frame to grip flower stems passing therethrough, and means for supporting the foundation on a garment.
- 25 4. A corsage holder comprising a clamping frame formed from a plurality of links pivoted to one another, resilient means acting on certain of said links to normally collapse said clamping frame to grip flower stems passing therethrough, a foundation, means for attaching the foundation to a garment, and a plurality of mounting links one end of each of which is pivoted to the foundation with its other end pivoted to the clamping frame.
- 30 5. A corsage holder comprising a center base link, lateral links having their closely adjacent ends pivotally connected to the opposite ends of the base link, lugs on the base link projecting beyond such pivotal connections and engaging with the lateral links to resiliently force the remote ends of the lateral links apart, and flower stem engaging means extending across the space between and secured to the remote ends of the lateral links.
